CLAIM

The ornamental design for a tool for automotive sensor manipulation, as shown and described.

DESCRIPTION

FIG. 1 is an isometric view of a tool for automotive sensor manipulation.

FIG. 2 is a top plan view of the tool for automotive sensor manipulation of FIG. 1.

FIG. 3 is a bottom view of the tool for automotive sensor manipulation of FIG. 1.

FIG. 4 is a front elevation view of the tool for automotive sensor manipulation of FIG. 1.

FIG. 5 is a rear elevation view of the tool for automotive sensor manipulation of FIG. 1.

FIG. 6 is a left side elevation view of the tool for automotive sensor manipulation of FIG. 1.

FIG. 7 is a right side elevation view of the tool for automotive sensor manipulation of FIG. 1.

FIG. 8 is a cross-sectional front elevation view of the tool for automotive sensor manipulation of FIG. 1, taken on the line 8-8 in FIG. 2; and,

FIG. 9 is a cross-sectional rear elevation view of the tool for automotive sensor manipulation of FIG. 1, taken on the line 9-9 in FIG. 2.

The dash-dash broken lines depict portions of the tool for automotive sensor manipulation that form no part of the claimed design. The dash-dot-dash broken lines illustrate the boundaries of the claim and form no part thereof.
